UNITED STATES PATENT OFFICE.

ALFRED J. FRUEH, OF NEW YORK, N. Y.

FIGURE TOY.

1,277,401.

Specification of Letters Patent. Patented Sept. 3, 1918.

Application filed December 22, 1916. Serial No. 138,350.

To all whom it may concern:

Be it known that I, ALFRED J. FRUEH, a citizen of the United States, and a resident of the borough of Manhattan, city, county, 5 and State of New York, have invented certain new and useful Improvements in Figure Toys, of which the following is a specification.

My invention relates to toys and has for 10 its object to provide a toy capable of being rocked or otherwise set in motion and comprising a plurality of components combined to form one character—human or animal—or one scene, or groups of such characters 15 and of such scenes, or a combination of both. A further object of my invention is to construct the toy in such a manner that one or more components thereof will be capable of a movement relatively to the other 20 parts of the toy as the latter is set in motion, whereby various effects are produced in the group, scene, or the like, represented by the toy. A still further object of my improvement is to arrange the various components or parts of such components in such 25 relation to each other as to produce life-like and natural groups, scenes, or combinations of both in the form of a toy. My improvement will be fully described hereinafter 30 and the features of novelty will be pointed out in the appended claims.

In the accompanying drawings, which illustrate an example of my improvement, Figure 1 is a front elevation of the toy; 35 Fig. 2 is a vertical section on the line 2—2 of Fig. 1, and Fig. 3 is a rear elevation of said toy.

The illustrated example shows the toy 40 constructed to represent characters and elements set forth in the well known nursery rhyme commonly known as "Sing a Song of Six Pence", and depicts the scene at the moment the pie was opened and the birds began to sing. It will, of course, be understood 45 that this specific arrangement has been selected merely for descriptive purposes and that other nursery rhymes, other topics or the like may be utilized as a basis of construction.

As shown in the drawings the toy 50 comprises a base 5 (Fig. 2) having a curved surface 6 upon which it may oscillate or rock, motion being imparted either manually or, if continuous movement is desired, 55 for instance when the device is used for dis-

play or advertising purposes, by means of suitable mechanism. One component of the toy may be attached to one of the upright surfaces of the base 5 and in the example comprises a flat section 7 continued upwardly beyond said base as indicated at 8, the projecting flat portion being fashioned to represent the broken crust of a pie and a plurality of singing black birds 9 breaking therethrough. The illustrated toy 60 further includes flat members 10 pivoted at 11 upon the inside surface of the projecting portion 8 and extending above the same, the members 10 in the present case being fashioned to represent the heads and necks 65 of black birds. At their lower ends the said members are preferably weighted either by means of weights 12 attached thereto or in any other way to always return said members 10 to an upright position or the position 70 occupied when the toy is at rest. With this arrangement the members 10 simulate singing birds breaking through the pie crust and capable of a pivotal movement on the pivots 11 relatively to the projecting 75 portion 8 as the toy is set in motion.

The toy in the illustrated example includes, in addition another flat section 13 which may be attached to the rear face of the base 5 and project upwardly beyond the 80 same in the form of a flat extension 14 as shown in Fig. 2. This extension 14 in the present instance is fashioned to represent the body and raised arms and hands of a 85 human figure, supposed to be the king in 90 the nursery rhyme hereinbefore referred to. Still another flat section 15 is attached to the front surface of the extension 14 at its upper portion and in the present case is fashioned to represent the head of the human body 14 with a crown thereon. The head section 15 is provided with eye sockets 16 extending transversely therethrough and located in registry with an aperture 17 95 formed in the extension 14 and which forms 100 therewith a recess as shown in Figs. 2 and 3. In the illustrated example two disks 18 are located in the recess 17 and they are independently movable therein or in other words are capable of rolling in said recess 105 independently of each other in registry with the eye sockets 16. Each disk 18 has an eye 19 produced on the surface which is adjacent to the section 15, which eyes 19 are visible through the sockets 16 as shown in Fig. 110

1. Any means may be used for maintaining the disks 18 in the recess 17 as for instance a strip of material 20 extending longitudinally across said recess and secured in 5 position for instance by nails or the like 21 as shown in Fig. 3. If desired a stop 22 may be located in the recess 17 at an intermediate point as illustrated in Fig. 3, for the purpose of arresting the movement of 10 each disk in one direction, the movements in the opposite directions being stopped by the end walls of the recess.

With the arrangement described it will be seen that different components of the toy 15 are located in different vertical planes extending parallel to the plane in which the toy rocks, as may be seen from Fig. 2, whereby the group or the scene is represented by the toy in an extremely natural 20 manner. For instance the toy as illustrated very graphically and naturally represents the opened pie from which the black birds extend in an attitude of singing in front of the king, who looks down upon the pie 25 with his hands and arms thrown upwardly in an attitude of surprise. As the toy is set in motion the disks 18 roll to and fro sidewise in the recess 17, thus causing the eyes 19 to change their positions relatively 30 to the sockets 16 and to produce many curious and amusing effects. At the same time the members 10 are independently oscillated upon their pivots 11 under the influence of the moving or rocking of the whole toy 35 whereby life-like movements are imparted to the birds represented by these members 10, which movements add to the graphic effects of the scene.

It will, of course, be understood that instead of being separate elements secured in 40 position, the projecting portion 8 and extension 14 may be formed as integral parts of the base 5 by suitably fashioning the latter as will be readily apparent, the 45 relative location in either case being the same. If the elements referred to are constructed as in the illustrated example the lower edges of the sections 7 and 13 are curved to register with, or to be parallel to, 50 the curved surface 6 of the base 5. It will also be obvious that the components of the toy may be carried by the base in other relations than as shown and that said components may project upwardly therefrom, 55 otherwise than from opposite surfaces. The toy need also not be a rocking toy but may be constructed to partake of other motions whereby the movable parts are given relative movements to produce the desired effects. 60 It will further be apparent, if the toy includes the representation of a human being that the position or action of the latter in the scene may predetermine for instance the number of eye disks 18 which are necessary, 65 that is, a figure represented, for instance,

in side view or in a front view, but working or closing one eye, may need only a single disk and a single eye socket 16.

My improved toys are extremely simple in construction and present very realistic 70 effects and may be utilized for amusement, for educational or for display purposes.

Various changes in the specific form shown and described may be made within the scope of the claims without departing 75 from the spirit of my invention.

I claim:

1. A toy comprising a base having a curved surface upon which it may rock, a main element representing a living thing 80 extending upwardly therefrom and provided with an eye socket and with a recess extending across and in registry therewith, a disk having the representation of an eye thereon movable in said recess in registry 85 with said socket, and auxiliary elements forming components of the group or scene of which the toy is a representation, said auxiliary elements including movable devices and being arranged in proper correlation to said main element to complete the 90 group or scene.

2. A toy comprising a base having a curved surface upon which it may rock, a main element extending upwardly from said 95 base in a vertical plane parallel with the plane in which said base may rock, said main element representing the body of a human being and being provided with a recess, a head section secured in surface engagement with the upper portion of said main element and located in an adjacent vertical plane parallel to the first plane, said head section being formed with eye 100 sockets in registry with said recess, a pair of eye disks adapted to roll in said recess, independently of each other and in registry with said eye sockets, means for maintaining said disks in said recess, an auxiliary element located in a vertical plane different 105 from and parallel with the first two planes and an element movable relatively to said auxiliary element and located in a vertical plane different from and parallel with the previously mentioned planes. 110

3. A toy comprising a base having a curved surface upon which it may rock, a main element extending upwardly from said 120 base in a vertical plane parallel with the plane in which said base may rock, said main element representing the body of a human being and being provided with a recess, a head section secured in surface engagement with the upper portion of said main element and located in an adjacent 125 plane parallel to the first plane, said head section being formed with eye sockets in registry with said recess, a pair of eye disks adapted to roll in said recess, independently of each other and in registry with said eye 130

sockets, means for maintaining said disks in said recess, and an element located in a vertical plane different from and parallel with the previously mentioned planes and 5 movable relatively to said main element.

4. A toy comprising a base arranged to be set in motion, a main element representing a living thing extending upwardly from said base and including movable parts 10 adapted to be set in motion as a result of the motion of said base, and auxiliary elements forming components of the group or scene of which the toy is a representation, and arranged in proper correlation to said 15 main element to complete the group or scene, said auxiliary elements including movable devices arranged to be set in motion as a result of the motion of said base and concurrently with the movable parts of 2 said main element.

5. The combination of a movable member representing a living thing having eye sockets and a plurality of disks each having the representation of an eye thereon and arranged to roll independently of each other 25 transversely to the axis of and in registry with said sockets as said member is moved.

6. A toy comprising a base capable of being set in motion, a representation of a living thing carried by said base and provided with eye sockets and with a recess in registry therewith and a pair of disks each having the representation of an eye thereon, said disks being movable independently of each other in said recess in registry with 35 said sockets when the toy is in motion.

In testimony whereof I have hereunto set my hand.

ALFRED J. FRUEH.
